UNITED STATES PATENT OFFICE.

MICHELLE E. BYRON, OF PEPPERELL, MASSACHUSETTS, ASSIGNOR OF ONE-HALF TO ALCIDE PROVENCHIER, OF MANCHESTER, NEW HAMPSHIRE.

MACHINE FOR STAMPING SOLES OF BOOTS OR SHOES.

SPECIFICATION forming part of Letters Patent No. 402,803, dated May 7, 1889.

Application filed November 15, 1888. Serial No. 290,976. (No model.)

To all whom it may concern:

Be it known that I, MICHELLE E. BYRON, of Pepperell, in the county of Middlesex and State of Massachusetts, have invented a new and useful Improvement in Machines for Stamping upon the Soles of Boots or Shoes, which invention I will describe as follows, reference being had to the accompanying drawings, which form a part of this specification, like letters indicating like parts in the different figures thereof.

Figure 1 of the drawings is in perspective and shows my machine when out of gear. Fig. 2 is partly in elevation and partly in section, and shows the machine in gear and as it appears when in operation. Fig. 3 is to illustrate the oscillating of the block that holds the dies. Fig. 4 is an enlarged perspective of one of the die-blocks. Fig. 5 is a vertical longitudinal section showing the block for holding the dies, the two die-blocks, and the screw for moving said die-blocks apart or toward each other, which screw has a right thread for half its length and a left thread upon the other half. Fig. 6 is an end elevation showing the block which holds the dies and the method of supporting and holding said block. Fig. 7 is a bottom plan of the dies and blocks. Fig. 8 is a plan of the cam, which is an important factor in turning off the standard which holds the boot after the sole thereof has been stamped, all of which is hereinafter fully described.

My invention consists in a device for stamping the soles of boots or shoes, the dies for such stamping being so constructed and adjusted that the marks, letters, or numbers produced by the dies severally shall be as near together or as far apart upon the sole of the boot as desired, and that the dies will adjust themselves to the sole of the boot exactly, whether said sole be made more or less convex in shape.

My invention also consists in a mechanism for pressing the dies upon the sole of a boot or shoe, lifting the same from said sole, and automatically throwing off the standard that holds the boot from under the dies when the operation is completed; also, a method of adjusting the standard that holds the boot to

provide for stamping soles of different thickness.

A is a pulley connected with the source of power by the belt B, said pulley serving as a loose pulley when the machine is out of gear and a tight pulley when it is in gear. This pulley is made fast to the shaft A', and the gear A² is also fast upon said shaft, all of which is fully shown in Fig. 1 of the drawings.

E is an eccentric gear upon the shaft E'. The shifter C has its inner end made in the shape shown at the point c, as shown in Figs. 1 and 2, for the purpose of holding the shaft E' when the machine is out of gear. The spring C' raises the outer end of the shifter C, and thus enables the end c of the shifter to hold the shaft E' and keep the machine out of gear. It will be observed that the arm D moves upon the shaft d, as shown in Figs. 1 and 2, and said arm, together with the eccentric gear E, is attached to the shaft E'. Thus it will be readily seen that when the operator presses his foot upon the end c' of the shifter C, and thus raises the opposite end thereof, the spring D' draws the lower end of the arm D back, and with it the eccentric gear E, both being upon the same shaft, E', so that said eccentric gear meshes in the gear A², and the machine is then in gear, as shown in Fig. 2.

When the operator removes his foot from the shifter C, said shifter is brought down upon the shaft A' by the action of the spring C' and is ready to again take hold of the shaft E' when said shaft shall come round with the eccentric gear E.

G is a standard, upon the upper end of which is placed the boot the sole of which is to be stamped. After the boot is placed thereon the operator turns with his hand the standard G, so as to bring the boot under the dies i i, as shown in Fig. 2. The screw g, turned by means of the wheel g² or by any other suitable device, is for the purpose of adjusting the standard G under the dies i i, to allow for the different thickness of the soles of boots. The spring g' (fully shown in Fig. 2) is for the purpose of cushioning the standard G.

The cam G' (shown in Figs. 1, 2, and 8) is

an important feature in this machine. It is made fast round the standard G, so that it moves with said standard. When the standard is under the dies *i i* ready for work, 5 this cam G' has the pin *h* for a bearing. The rod II is held to the frame L of the machine by the pivot *h*² and moves upon this pivot. Near the upper end of the rod II is the arm *h'*, said arm being provided with a spring, *h*⁵, 10 as shown clearly in Figs. 1 and 8, to prevent breakage when it comes back and strikes the cam G'. An examination of Fig. 2 shows the rod *m* connected with the rod II by and moving upon the pivot *h*³, the opposite end of said 15 rod *m* being held to the arm D in and by means of the slot and set-screws shown at *m'*. This rod *m* may thus be held to the arm D at right angles therewith, or may be moved up or down to regulate the rapidity with which 20 the arm D will be drawn back after the operation of stamping has been accomplished.

The operation of the part of my machine the construction of which has just been described may be explained as follows: The machine is placed in gear by the operator pressing his foot upon the shifter C at the point *c'*, as has been hereinbefore fully described. Now that the machine is in gear and the eccentric gear E meshes in the gear A², and said 25 eccentric gear is attached to the same shaft, E', to which the lower end of the arm D is held, it is obvious that the eccentric gear first moves the lower end of the arm D outward, and as said arm D is moving upon the pivot *d* the effect is to bring the dies *i i* down upon 30 the sole of the boot which is upon the end of the standard G and with such power as to stamp said sole. After the dies have done their work upon the sole of the boot, the spring 35 D' draws said arm D back, and this arm D, being connected with the rod II by means of the rod *m*, said rod II is forced back, the arm *h'* strikes the cam G', and the standard G is turned around so that the boot may be re- 40 moved therefrom and another be placed thereon. The pieces designated *a* are merely to form a guide to the arm D.

A very important part of my invention relates to the construction, arrangement, and 45 operation of the dies for stamping, to which reference has been previously made.

For brevity in the description I designate the dies and the blocks to which they are attached together as *i i*, as a block and its die 50 are practically one thing.

I is the main block, and *i'* is a slot in the arm D, in which there should be sufficient room for the block I to oscillate. This is fully illustrated in Fig. 3. The bolt *d'* is to 55 hold the block I in place, and is pivoted to said block at the point *I'*, as shown in Fig. 6, to admit of the oscillation above mentioned. The spring *d*² is for the purpose of cushioning.

60 M is a screw inserted partly in the main block I and partly in the die-blocks *i i*. The

screw works, however, in the die-blocks, the slot in the main block I being only a smooth slot. At the end of the screw M there should be some suitable handle for turning, as M'. 70 The pin *n*², working in the slot *n'*, is for the purpose of holding the screw M when it is turned to the desired point.

An examination of the drawings, especially of Figs. 5 and 7, will show that the screw M 75 has a right thread for half of its length and a left thread for the other half. By this arrangement it is obvious that by turning the screw M one way or the other the dies *i i* may be placed near together or far apart, and thus 80 the letters, figures, or marks produced by each die may be made to appear as near together or far apart upon the sole of a boot as desired.

The two springs *n*³ *n*³ (shown clearly in Fig. 85 5) are equalizing-springs, each one bearing upon the block I in one direction and upon a plate between said spring and its adjusting-bolt *n* in the other direction. The bolts *n n* are for regulating the tension of the equalizing-springs *n*³ *n*³. When the dies *i i* are brought down upon the sole of a boot, the oscillating of the main block I, regulated by the two equalizing-springs *n*³ *n*³, the tension of which is governed by the bolts *n n* with their 90 nuts *n*⁴ *n*⁴, makes it certain that the dies *i i* will be placed fully and completely upon the sole of a boot, and thus the fullness and completeness of the stamp upon said sole will be secured, whether said sole be more or less 95 convex in form.

Having fully described my invention, what I claim as new, and desire to secure by Letters Patent, is—

1. In a machine for stamping the soles of 105 boots or shoes, the main block I, oscillating in the slot *i'* and provided with the adjustable equalizing-springs *n*³ *n*³, the die-blocks *i i*, moved by means of the screw M, which is provided with a right and left thread upon 110 each half of the screw, respectively, in combination with the arm D, and the standard G, constructed and arranged substantially as described and shown, and for the purposes set forth.

2. In a machine for stamping the soles of 115 boots or shoes, in combination, the arm D and eccentric gear E, both attached to the shaft E', the shifter C, provided with the spring C', the gear A², attached to the shaft A', the spring D', the rod II, equipped with the arm *h'* and connected with the arm D by the adjustable rod *m*, the cam G', made fast to the standard G, said standard being provided with the adjustable screw *g* and with 120 the cushioning-spring *g'*, the whole constructed and arranged substantially as described and shown, and for the purposes set forth.

MICHELLE E. BYRON.
